UNITED STATES PATENT OFFICE.

EUGEN SECKLER, OF PHILADELPHIA, PENNSYLVANIA.

COMBER BOARD.

Application filed May 12, 1926. Serial No. 108,494.

My invention relates to new and useful improvements in a comber board structure for looms, and has for its primary object to provide such a device which will permit the harness cords to be adjusted relative to each other in order to maintain the heddles in an even plane.

Another object of the invention is to provide a comber board structure wherein three frames are utilized, arranged in spaced positions above each other, the lower and upper ones of said frames having a longitudinal group of wires in staggered relation, and also provided with a plurality of movable groups of wires slidable longitudinally of the frames whereby the harness cords may be moved into different vertical positions; the central board having only the movable groups of transversely arranged wires, whereby portions of the harness cords may be moved out of the vertical positions to compensate for any variance in the vertical positions of the heddles relative to one another.

A further object of the invention is to generally improve the construction of the wire mounting or frames of the comber board structure.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a fragmentary plan view of one of the frames with a portion of one of the strips removed to illustrate a detailed construction.

Fig. 2, is a similar view of another of the frames.

Fig. 3, is an enlarged transverse sectional view of Fig. 1.

Fig. 4, is an enlarged transverse sectional view of Fig. 2.

Fig. 5, is a perspective view of one of the end members of the movable wire groups.

Fig. 6, is a perspective view of one of the spacing panels.

Fig. 7, is a front elevation of a jacquard machine with some of the harness cords pending therefrom, and showing the manner

in which these and additional cords pass through the comber board structure when adjusted for weaving a wide fabric.

Fig. 8, is a diagrammatic view of the harness cords shown in Fig. 7, illustrating the 60 adjustments that are made for weaving a narrow fabric.

Fig. 9, is a diagrammatic view of a less number of harness cords illustrating the positions assumed by the different heddles during the adjustment from one extreme to the other.

Fig. 10, is also a diagrammatic view similar to Fig. 8, illustrating an adjustment for weaving an intermediate width of fabric, 70 and illustrating the manner in which the harness is adjusted to bring the heddles into the same horizontal plane from the positions assumed in Fig. 9.

In carrying out my invention as herein embodied, 15 represents a suitable frame, the two longer sides of which are rabbeted on the inside, and over which extends portions of the strips 16 to form guide grooves 17 for a purpose to be presently described. 75 Within this frame is arranged a stationary group of longitudinal wires or rods 18, running from one end to the other, and the several wires of this group are arranged in staggered relation to each other, as plainly 80 shown in Fig. 3, and are supported within the frame by means of lateral strips 19, suitably apertured to receive the wires, and the majority of these strips are supported at their ends in the channel guides 20 secured 85 to the inner faces of the longer sides of the frame, but terminating short of the ends, as indicated in Fig. 1, so as to leave passageways 21 to the guide grooves 17, because the upper edges of the channel guides 20 project above the lower walls or faces of the 90 guide grooves. It is to be understood that the strips 19 are adjustable or slidable on the wires 18.

In the guide grooves 17 are slidably 100 mounted the end members or carriages 22 of the movable groups or transversely arranged wires and may be entered into the guide grooves through the passageways 21. These carriages are preferably made from channel 105 sections and are provided with a plurality of staggered holes 23 for the reception of the ends of the transverse wires 24. These transverse wires with their carriages are slidable longitudinally of the frame 15, and in order 110

to maintain them in their spaced relation to each other, a panel 25 having holes 26 there-thru, corresponding to the holes 23 in the carriage is mounted on the wires intermediate their ends, and projects between some of the longitudinal wires 18, and if found desirable, guide wires 27 may be provided so as to form spaces into which the panel projects, which spaces will be approximately the same size as the thickness of the panel, whereas the distance between the comber board wires may be considerably greater.

There are a number of the movable groups of transverse wires in the frame, and one or more of them may be located between the cross strips 19.

The several groups of movable transverse wires crossing the stationary group of longitudinal wires form numerous holes for the harness cords, and because of the staggered relation of the wires in the several groups a greater number of holes are provided in a given space than would be possible if all the wires were in one straight line.

25 The frame illustrated in Figs. 2 and 4, and designated by the numeral 28, is the same as the one above described, with the exception that the longitudinal comber wires are eliminated, and only four guide wires 27^a are used 30 to guide the panel 25 of each group of transverse wires.

In actual practice, two frames 15 are used, with one frame 28 between them in spaced relation as shown in Figs. 7 to 10 inclusive, being supported in vertical alignment between suitable brackets or frame work (not shown) generally used in devices of this character.

40 In Fig. 7, the jacquard machine 29 is shown as provided with hooks 30, from which depend the harness cords 31, and these pass through the holes formed by the several groups of wires in the upper frame 15, then through the movable groups of transverse wires in the frame 28, and then 45 through the holes between the several groups of wires in the lower frame 15, and because the movable groups of wires in the lower frame are set in the major separated positions, the harness cords are located for weaving wide fabric, and heddles 32 are in the same horizontal plane, or substantially so. When it is desired to weave a narrow fabric, the groups 20 of movable transverse wires 50 are slid toward each other, or toward a central point so as to bring them closer together, and the outermost ones of these movable groups of wires can be moved the same distance to one side of a vertical center as they were to the other side of such vertical center when weaving the wide fabric, without making any adjustments in the central frame, and, as will be obvious, upon reference to Fig. 9, the heddles are out of alignment 55 when in the intermediate positions

prior to adjustment of the mechanism in the central frame 28. In order to bring the heddles back into the same horizontal plane after the harness has been adjusted for weaving a fabric of a width between the narrow- 70 est and widest ones, the groups of movable transverse wires in the middle frame 28 are moved away from the central harness cord, and therefore give a zigzag formation to said cords, to pay up or compensate for the 75 differences in the lengths of said cords when in the intermediate position, as shown in Fig. 10.

After the movable groups of wires have been adjusted as desired, spacing sticks 33 80 may be placed between the several groups so that the ends of said sticks set into the guide grooves 17 and lie between the ends of the carriages 22 thereby holding said groups of wires in their proper spaced relation.

In Figs. 7, 8 and 10, the lower ends of a number of harness cords are shown without running them from the hooks because of the likelihood of confusing the illustration.

Of course I do not wish to be limited to 90 the exact details of construction as herein shown as these may be varied within the limits of the appended claims without departing from the spirit of my invention.

Having thus fully described my invention, 95 what I claim as new and useful is:

1. A comber board structure including a pair of supporting elements in spaced relation, means to provide guide holes for harness cords; an intermediate supporting 100 structure, and means in the latter supporting structure to change the positions of the intermediate portions of the cords to vary the positions of their lower ends.

2. A comber board structure including upper and lower frames; longitudinal spaced wires supported in said frames in staggered relation; transverse wires supported in staggered relation in each of the frames and arranged in groups, separately movable; another frame between the first mentioned ones; transverse wires in the central frame in staggered relation to each other and arranged in groups for separate movements; harness cords passing between the several groups of wires and provided with heddles; the movements of the groups of transverse wires changing the positions of the cords and aligning heddles thereof.

3. In a comber board structure, a frame 120 provided with guide grooves; channel guides secured to the inside of the frame adjacent the guide grooves so as to project above the lower walls of the latter, said channel guides terminating short of the ends of the frame 125 to provide passageways leading to the guide grooves; a plurality of parallel spaced wires in staggered relation; space strips in which said wires are mounted, the ends of said spacer strips being supported in the channel 130

guides; carriages slidably mounted in the guide grooves and insertable and removable therefrom through the passageways; a plurality of spaced parallel wires mounted in said carriages in staggered relation and crossing the first mentioned wires to form guide holes for harness cords; panels mount-

ed on the transverse wires and projecting between certain of the first mentioned wires; and spacer sticks insertible between the groups of movable wires.

In testimony whereof, I have hereunto affixed my signature.

EUGEN SECKLER.
